UNITED STATES PATENT OFFICE.

CHARLES H. WHITING, OF NEW YORK, N. Y.

STORAGE-BATTERY PLATE.

SPECIFICATION forming part of Letters Patent No. 789,514, dated May 9, 1905.

Application filed June 25, 1904. Serial No. 214,134.

To all whom it may concern:

Be it known that I, CHARLES H. WHITING, a citizen of the United States, residing at New York, in the county of New York and State 5 of New York, have invented a certain new and useful Improvement in Storage-Battery Plates, of which the following is a specification.

This invention relates to storage-battery plates or grids made thin and light to diminish the dead-weight and at the same time maintain the necessary rigidity and solidity of the plate or grid as a whole; and the invention pertains to that type of thin and light plates or grids consisting of a plurality of strips or 10 bars united with an end piece, the strips or bars having the receiving-surfaces for the active material running parallel with the outer side faces of the end piece of the plate or grid, such type of plate or grid being shown in the 15 20 Letters Patent to Achille Meygret, No. 760,897, dated May 24, 1904. The effectiveness of this type of plate or grid having depending strips with a definite space of separation between their side edges has been fully 25 tested and found to be practical in use. It has been found, however, more particularly in connection with plates or grids having the strips or bars of some length, that unless great care is taken in applying the active matter or 30 material the strips or bars will slightly flex or bend, so as not to lie in the same vertical plane, and also will in removing from the mold when cast often have the equidistance of the strips or bars disturbed, which while not 35 40 a detriment to the use of the plate or grid requires more care and attention in making the grids and applying the active material thereto.

The object of the present invention is to insure the maintenance of the strips or bars in the same parallel plane one with the other and without any liability of warping or curving out of a true parallelism for all of the strips or bars; and to this end the invention consists in tying together the adjoining side edges of the several strips or bars in such manner as not to destroy the effectiveness of the definite separation of one strip or bar from its adjacent strip or bar, as hereinafter more particularly described, and pointed out in the claims. 45 50

In the drawings, Figure 1 is a side eleva-

tion of a plate or grid without the active matter or material applied thereto and having the depending strips or bars tied together, so as to be held in the same parallel plane by a cross-tie at the lower end, one cross-tie in each 55 separating-space between the strips or bars; Fig. 2, a sectional elevation on line 2 of Fig. 1 looking in the direction of the arrow; Fig. 3, a similar view to Fig. 1, showing a plurality of cross-ties in each separating-space between the several strips or bars of the plate or grid; Fig. 4, a sectional elevation on line 4 of Fig. 3 looking in the direction of the arrow, and Fig. 5 a side elevation showing the lower end of a plate or grid having its receiving-faces formed with rectangular pockets or recesses and having a continuous cross-tie at the lower end by which the strips or bars will be held parallel one with the other.

The plate or grid shown is of a rectangular 70 form and is preferably made of thin metal cast, stamped, or otherwise shaped into form. The construction of plate shown has an upper end piece *a*, which furnishes a support for the depending strips or bars *b*, the end piece *a* and strips or bars *b* constituting the plate or grid as a whole. The outer side surfaces or faces of the end piece and the strips or bars are in the same plane, and each strip or bar has therein a series of openings or perforations *c*, which furnish passage-ways between the two opposite faces of each strip or bar for applying the active matter or material which when spread on the two faces of each strip or bar passes through the openings or perforations, thus forming a neck or web by which the active material will be held firmly in place; but instead of the body of each strip or bar having openings or perforations, as shown, such body could be otherwise made 80 85 so as to present cavities or spaces to receive and retain the active matter or material.

The end piece *a* and each strip or bar *b* have a border ridge or rib *d*, which serves to strengthen the plate or grid as a whole and adds to the rigidity of such plate when made of thin material, and these border ridges or ribs also form channels or depressions in which the active matter or material is spread on both sides of the plate or grid and is held 90 95 100

in place against side and end displacement by the ridges or ribs. The depending strips or bars are definitely separated one from the other by an intervening slot *e*, extending from 5 the lower edge of the end piece *a* the full length of the strips or bars, separating the vertical or longitudinal edges of the strips one from the other. This slot *e* between the vertical or longitudinal edges of the strips or 10 bars should be of a sufficient width to subdivide the area of active matter into divisions each separate and distinct from the other, by which arrangement the expansion and contraction of the active material on one strip 15 or bar will not be transmitted to the companion strip or bar and effect a loosening of the active matter or material on the several strips or bars. The expansion and contraction of the active material will only extend over the 20 dimensions of each strip or bar, thus reducing the expansion and contraction to a minimum as compared to a plate or grid in which the body is continuous or in one piece.

The rigidity of the strips or bars is sufficient 25 under ordinary conditions to prevent the side warping or flexing of the strip or bar, so as to be out of parallel with the remaining strips or bars; but where the strips or bars are of some length in order to have a positive 30 assurance that the strips or bars will not warp or curve out of true alinement some means should be employed for maintaining the alinement of the bars without affecting the definite separation of one strip or bar from 35 the other. This maintenance of the true parallelism or alinement of the strips or bars with each other is the object of the present invention and is attained by tying one depending strip or bar to its adjacent strip or bar by 40 a ligament or cross-tie, which will leave the definite space or separation virtually intact. This ligament or cross-tie *f* can be arranged in various ways to attain the result sought. As shown in Figs. 1 and 2, the ligament or 45 cross-tie *f* is located at the bottom of each defining-space *e* and unites the lower end of each strip or bar to the lower end of its adjacent strip or bar, with the result that the strips or bars are united at their upper end 50 and also at their lower end, with the definite space between the strips or bars remaining in its full effectiveness, thus insuring the maintenance of the strips or bars in true parallelism or alinement and against warping or curving, for one or more of the strips or bars to 55 be out of parallelism or alinement. In Figs. 3 and 4 a plurality of ligaments or cross-ties *f* are provided, which ligaments or cross-ties are so arranged as to leave the effectiveness 60 of the definite-spaced separation of one strip or bar from another intact. The plurality of ligaments or cross-ties *f* in the construction shown in Figs. 3 and 4 is more especially intended for use with plates having strips or 65 bars of great length, thus insuring the strips

or bars against flexing or bending, so as to be out of a true parallelism or alinement to an extent that will impair the efficiency of the battery-plate in use and the maintenance of the strips or bars in parallelism or alinement 70 in shaping or casting the grid and in applying the active matter or material. As shown in Fig. 5, the ligament or cross-tie is in the shape of a rib extending continuously across the lower ends of all the strips or bars, which ligament or cross-tie *f'* affords the same protection against warping or curving of the several strips or bars out of parallelism or alinement as does the individual ligament or cross-tie in each space *e* of the construction shown 75 in Figs. 1 and 2, the ligament or cross-tie *f'* of Fig. 5 serving the same purpose and attaining the same end with the same result as do the ligaments or cross-ties in the construction of Figs. 1 and 2. 80

It will be seen that with the present invention a grid for a storage-battery plate is furnished in which there is a plurality of strips or bars united with an end piece and definitely spaced apart or separated from each other a 90 small distance, which strips or bars are maintained in parallelism or alinement and against curving or warping by the tying together of the several strips or bars, and that such tying together does not impair the effectiveness and 95 operativeness of the plate as a whole, having its receiving-face made up of a plurality of strips or bars which present each an area of receiving faces or surfaces for the active material that will prevent the effects of expansion and contraction extending from one strip or bar to another strip or bar. The liability 100 of any curving or warping or flexing or bending that would break the parallelism or alinement of the several strips or bars one with the other is effectually guarded against, and this without any deteriorating effects on the definite spacing apart of the plurality of strips or bars. The active material can be applied 105 with the assurance that when the plate as a whole is finished the several strips or bars will be in parallelism or alinement one with the other and will be maintained throughout their entire length equidistant apart without any wavy separation between the strips or bars. 110 The ligament or cross-tie between the several strips or bars is a protection against breakage in shaping or casting the grid and in handling the plate or grid during the application of the active matter or material and 115 until the plate as a whole is completed ready for use, and when fully covered and coated, if so desired, this ligament or cross-tie can be severed, though if left intact it will not interfere with the operation of the plate when 120 in the battery. The plate or grid of the present invention by reason of bridging or cross-tying one strip or bar to its adjacent strip or bar adds utility and value, as it furnishes a positive assurance that the strips or 125

bars will be maintained in parallelism or alignment during manufacture, that they will be kept equidistant apart throughout their entire length without any liability of a wavy separation, and will be protected against breakage in the subsequent handling of the plate until its final completion ready for use.

The construction of plate or grid shown in Fig. 5 has each of its strips or bars formed with a plurality of longitudinal ribs *g* of the full thickness of the strip or bar, and between the longitudinal ribs on one face of the plate or grid is formed a plurality of cross-bars *h*, and on the opposite face of the strip or bar is formed a plurality of cross-ribs *i*, the cross-ribs *h* and *i* alternating and furnishing, with the longitudinal ribs, a series of pockets or depressions overlapping each other for the pockets or depressions to receive and retain the active material.

What I regard as new, and desire to secure by Letters Patent, is—

1. A grid for a storage-battery plate, consisting of an end piece and a plurality of strips or bars united with the end piece and definitely separated from each other a small

distance apart, each strip or bar adapted to receive the active material thereon with the receiving-surfaces for the material running parallel with the outer side faces of the end 30 piece of the plate and the several strips or bars held in proper relation one to the other by cross-tying adjoining strips or bars, substantially as described.

2. A grid for a storage-battery plate, consisting of an end piece and a plurality of strips or bars united with the end piece and definitely separated one from the other a small distance apart, each strip or bar adapted to receive the active material thereon with 35 the receiving-surfaces for the material running parallel with the outer side faces of the end piece of the plate, and a cross-tie at the lower end of the plate uniting the strips or bars at their lower end and serving to retain 40 the strips or bars in proper relation one to the other, substantially as described.
